UNITED STATES PATENT OFFICE.

WILLIAM F. SCOTT, OF MCKEES ROCKS, PENNSYLVANIA, ASSIGNOR OF ONE-HALF TO F. H. MCKINNIE AND S. D. ROBISON, OF SEWICKLEY, PENNSYLVANIA, AND C. W. ROBISON, OF MCKEES ROCKS, PENNSYLVANIA.

PORTABLE DRILLING-MACHINE.

SPECIFICATION forming part of Letters Patent No. 781,370, dated January 31, 1905.

Application filed March 24, 1903. Serial No. 149,356.

To all whom it may concern:

Be it known that I, WILLIAM F. SCOTT, a citizen of the United States of America, residing at McKees Rocks, in the county of Allegheny and State of Pennsylvania, have invented certain new and useful Improvements in Portable Drilling-Machines, of which the following is a specification, reference being had therein to the accompanying drawings.

This invention relates to certain new and useful improvements in portable drilling-machines capable of general application, but adapted especially for the drilling of hard metals, compressed air being employed as a motive fluid, provision being made for communicating rotation of the motor or power-wheel to the drill-chuck through the medium of interposed gears or other mechanism.

A further object of my invention is to provide novel means for feeding the compressed air or other motive fluid into the cylinder of the motor in such a manner that the full force of the same acts upon the blades or fans of the power-wheel whereby to obtain an exceedingly high rate of speed of this wheel, the interposed gearing or other driving mechanism between the wheel and the drill-chuck serving to decrease the number of revolutions of the drill-chuck, whereby the latter may be rotated at a materially less rate of speed than the power-wheel or piston.

My invention also contemplates improvements in the general construction of the device of this character whereby to obtain a greater efficiency from the same, among which is the provision of automatic oiling means for the bearings of the interposed gearing employed for decreasing the speed of the drill-chuck and in means for regulating the quantity of motive fluid admitted to the cylinder, together with the particular manner of introducing the fluid into the cylinder whereby to obtain a greater effectiveness and efficiency of the machine.

In describing the invention in detail reference is had to the accompanying drawings, forming a part of this specification, and where-

in like numerals of reference indicate like parts throughout the several views, in which—

Figure 1 is a central vertical sectional view 50 of my improved portable drilling-machine. Fig. 2 is a horizontal sectional view taken on the line 2-2 of Fig. 1. Fig. 3 is a longitudinal sectional view of the motive-fluid-controlling means. Fig. 4 is a cross-sectional view of the 55 same.

To put my invention into practice, I provide an annular casing 1, provided with a flange or rim 2 and the bottom or base 3 of which is provided with a bearing-hub 4 to receive the 60 driving-shaft 5 of the drill-chuck 6. This shaft 5 is mounted in suitable antifriction-bearings 7, the chuck being held by means of the screw-cap 8 engaging the hub. The bottom plate 3 of the casing or shell is provided 65 also with a hollow hub or extension 9, which forms an oil-reservoir and is closed at its outer end by means of a threaded block 10. Into this hollow hub or extension extends a stub-shaft 11, the lower portion of which is hollow 70 and which is provided with a passage way or port 12, leading through to the other end of the shaft. The said shaft is rounded at its upper end and engages the bearing 14 provided therefor, and on this shaft is mounted a gear 75 16 and pinion 17, which mesh, respectively, with the gear 18 on the shaft 5 and the pinion 19 on the stub-shaft 20. This stub-shaft 20 is carried in the hub 21 of the motor or power-wheel, which wheel embodies a hub and the 80 integral curved vanes or blades 22, the ends of which contact with the annular shell 23, the lower edge of which rests on the plate 24 and the upper edge of which is integral with the top plate 25, having a flange 26, which is firmly 85 secured by bolts 27 to the plate 24 and flange 2 of the annular casing 1. These tie-bolts 27 are preferably passed through sleeves or casings 28, interposed between the flange 26 and the plate 24. The hub 21 is provided with 90 suitable antifriction-bearings 29, and a feed device 30 is provided with suitable antifriction-bearings 31. This feed device is of the ordinary construction, embodying a sleeve

having a pointed upper end, which may be engaged with any suitable object, and provided with handles on its periphery, which sleeves receive the threaded screw extending through 5 the top plate or cover of the cylinder. The annular shell 23, inclosing the cylinder, is provided with inlet-ports 32 33 at opposite sides of the shell and project through the shell at an angle in different directions, whereby the 10 motive fluid admitted through one inlet-port is projected into engagement with one of the vanes or blades and the motive fluid admitted through the other port is projected into engagement with another of said vanes or blades, 15 both driving in the same direction. A suitable outlet or exhaust port 34 is provided at any desired point between the two inlet-ports in the wall of the shell 23.

The motive fluid is fed to the inlet-ports 20 simultaneously, and to this end the feed-pipe 35, which is connected to both of the ports 32 33, has attached thereto the union 36, and for controlling the quantity of motive fluid admitted I preferably employ a regulating device embodying a tube 37 connected to the union 36 and provided intermediate its ends with a partition 38. The tube is provided in its walls at each side of this partition with ports 39, and mounted on the tube for rotation thereon is a sleeve 40, provided with ports 41, adapted when the sleeve is in one position to establish communication through ports 39 on one side of partition 38 across the ports 39 at the other side of the partition and when 35 the sleeve is given a one-quarter turn adapted to cut off communication either partially or wholly between these points, and thereby either regulating or entirely shutting off the quantity of motive fluid admitted.

40 It will of course be evident that when the tool is being used in the inverted position from that shown in Fig. 1 the oil contained in reservoir 10 will readily feed through the port 12 to lubricate the bearing 14, and in 45 practice I have found that when used in position as shown in Fig. 1 this bearing is always lubricated, as a sufficient quantity of the

compressed air always escapes, which in its attempt to find exit passes in around the lower end of shaft 11, whereby to elevate the oil and 50 force the same up the passage 12.

I desire to call particular attention to the manner in which the motive fluid is projected into the cylinder and into engagement with the vanes or blades of the piston or power-wheel. This air striking these blades or vanes 55 in the manner as will be observed by reference to Fig. 2 exerts the fullest possible extent of its power thereon, whereby to impart an exceedingly great revolution of the power-wheel or piston and derive the greatest possible efficiency from the same. Through the medium of the intermediate gearing the drill-chuck is geared down, whereby the drill will be driven at a rate of speed consistent with 60 that required for this class of work.

In order that the device can be conveniently handled, I provide a side handle 42, as well as the handles employed on the feed device.

Having fully described my invention, what 70 I claim as new, and desire to secure by Letters Patent, is—

In a device of the character described, a circular casing having an air-chamber, air-supply pipes leading to inlets in the casing 75 opening into said air-chamber at diametrically opposite points, a wheel arranged in the air-chamber and consisting of a hub and three curved wings, each wing being disposed in a direction substantially tangential to the hub 80 and with their concave sides toward the air-inlets, whereby the incoming air will strike the wings substantially on a direct line from the time it enters the chamber until it exhausts from same, and the said casing having an air-outlet located between the said air-inlets, 85 whereby dead-air spaces are avoided.

In testimony whereof I affix my signature in the presence of two witnesses.

WILLIAM F. SCOTT.
